UNITED STATES PATENT OFFICE.

JOSEPH L. BUCKLEY, OF TRENTON, NEW JERSEY, ASSIGNEE, BY EXPRESS ASSIGNMENTS, TO PROCTOR & SCHWARTZ, INCORPORATED, OF PHILADELPHIA, PENNSYLVANIA, A CORPORATION OF PENNSYLVANIA.

DRYING APPARATUS.

Application filed January 23, 1923. Serial No. 363,526.

To all whom it may concern:

Be it known that I, JOSEPH L. BUCKLEY, a citizen of the United States, and resident of Trenton, in the county of Mercer and State of New Jersey, have invented a new and useful Improvement in Drying Apparatus, of which the following is a specification.

This invention relates to an improvement in apparatus for drying or conditioning articles composed of clay, porcelain or the like with the object in view of providing such an apparatus which occupies a minimum of floor space, while being capable of rapidly 10 and simultaneously drying a large number of articles.

Another object is to provide apparatus of this character, in which the articles to be dried may be progressively subjected to varying 20 conditions in order to produce a uniform product.

Another object is to provide such an apparatus in which the articles to be dried may be subjected to the action of the drying air current under varying conditions and in varying positions.

Another object is to provide such an apparatus in which the drying air currents are given a predetermined course and are confined within a given space.

Another object is to provide such an apparatus in which the molds for holding the articles to be dried may be cooled after their load has been discharged and before they are 30 reloaded.

Another object consists in providing such an apparatus in which the drive shaft for the means that carry the articles is separable from the drive for the fan which produces the air current, so that the latter may be actuated even when the former is idle.

Another object consists in providing certain improvements in the form, construction and arrangement of the several parts whereby the above named and other objects may be effectively attained.

A practical embodiment of the invention is represented in the accompanying drawings, in which

Fig. 1 represents a top plan view of the apparatus.

Fig. 2 represents a longitudinal vertical section of the same, partly in elevation.

Fig. 3 represents a side elevation of the same.

Fig. 4 represents a section taken in the plane of the line IV—IV of Fig. 2, looking in the direction of the arrows, the articles to be dried and their molds being shown in dotted lines.

Fig. 5 represents an elevation, partly in section, of one of the plates which constitute walls of the apparatus.

Fig. 6 represents an enlarged detail section taken in the plane of the line VI of Fig. 5, looking in the direction of the arrows.

Fig. 7 represents an enlarged end elevation of one of the trays for carrying the articles to be dried.

Fig. 8 represents a detail elevation, partly in section, of the same.

Fig. 9 represents a section taken in the plane of the line IX—IX of Fig. 8, looking in the direction of the arrows.

Fig. 10 represents a detail vertical section of a modified form of apparatus.

Fig. 11 represents an enlarged detail plan view of the form of tray used in the modified form of apparatus shown in Fig. 10.

Fig. 12 represents a transverse section of the same, parts being shown in different positions in full and dotted lines.

Fig. 13 represents a detail elevation of the same, the articles being shown in dotted lines.

Fig. 14 represents a detail elevation of the same, partly in section, with the tray shown in an inverted position.

Fig. 15 represents a longitudinal vertical section, partly in elevation, showing a second modified form of apparatus.

Fig. 16 represents a detail elevation of a second modified form of tray for carrying articles, the latter being shown in dotted lines.

In Figs. 1, 2, 4, 10 and 15, the walls of the housing 1 are shown conventionally, but it will be understood that they are intended to be of the construction represented in Figs. 3, 5 and 6, to be hereinafter described.

Referring to the form shown in Figs. 1

to 9 inclusive, the apparatus includes a rectangular enclosure or housing 1 which may be composed of a frame-work consisting of angle irons 2 and plates 3. Each of the plates 3 preferably consists of an outer member 4 and inner member 5 crimped together at their peripheries as indicated at 6. The space between the members 4 and 5 is filled with thermo-insulating material such as 10 corrugated sheets of asbestos disposed cross-wise with respect to each other. Suitable holes 3* may be formed in the plates 3 to permit the passage of steam pipes for the radiators to be hereinafter described.

13. These plates may conveniently be secured to the angle iron frame-work by means of bolts 8 projecting from the angle irons, clamps 9 fitting over said bolts and wing nuts 10 threaded onto the bolts. This fastening arrangement permits the plates or panels 3 to be removed if desired. I prefer to have the inner members 5 of the plates 3 composed of galvanized iron and to have any openings into the interior of 25 the said plates or panels 3, which may be made during the fitting of the parts, soldered. This prevents rusting of the interior of the enclosure and also prevent access of moisture to the asbestos sheets 7, 30 which moisture, if permitted to attack the said sheets, would reduce their insulating quality.

The construction just described constitutes a strong and easily assembled enclosure 35 which is dust-proof on the interior and substantially without radiation of heat on the exterior.

Means is provided for generating a current of air within the enclosure and this 40 means consists of a fan 11 that is carried on a spindle 12, which is journaled in a ball bearing 13 mounted in the top of the enclosure. A collar 14 is pinned to the spindle 13 and rests in the top of the bearing 13 in order to properly support the spindle 12 therein.

The mounting for the bearing 13 consists of a pair of transverse channel irons 15, 16, secured at their ends to the framing 50 of the enclosure 1. The bearing 13 has a shoulder 13* formed thereon, which rests on top of and may be bolted to the upper flanges of the channel irons. This bearing 13 passes through the roof of the enclosure 55 with a close fit.

The drive for the spindle 12 which carries the fan 11 consists of a pulley 17 that is pinned to the spindle, a belt 18 and pulley 19, the latter being fixed on a shaft 60 20 and the belt 18 engaging both said pulleys. The shaft 20 is driven by an electric motor 21 that is mounted on legs 22 on cross members 23, fixed to the top of the enclosure 1. A belt 24 runs from the motor to a 65 pulley 25 fixed on the shaft 20.

The fan is driven so as to direct an air current downwardly and means is provided for causing the air current to follow a predetermined endless course. This means consists of a pair of partitions which are 70 substantially U shaped in cross section, mounted one within the other in oppositely disposed relationship. The inner partition is denoted by 26 and has a circular shield 27 secured in an aperture formed in the top 75 thereof, which shield surrounds the fan 11 in close proximity to the extremities of the blades thereof. This partition 26 is supported by angle iron members as indicated at 28 and is arranged like an inverted U so that the bottom thereof is entirely open. The walls of the partition are preferably composed of galvanized steel and extend transversely from side to side of the enclosure 1, so that there is little or no chance for the air current generated by the fan 11 to escape from the partition 26 at any place except the bottom thereof. It will be noted that the lower part of the partition 26 is greater in width than the 85 diameter of the shield 27, and that the upper part of the partition slopes into the said shield in such a manner as to avoid the formation of a right angle. This is indicated at 29, and the purpose of this formation is to obviate the existence of air pockets which would be likely to occur in the 90 case of a right angular formation.

The other, and larger partition, is indicated by 30 and is of substantially the same 100 form in cross section as the partition 26. It encompasses the smaller partition 26 and is oppositely disposed with respect to the latter so that its open part is at the top instead of the bottom. The larger partition 105 30 is also slightly eccentric with respect to the partition 26, so that there is a greater distance between the walls of the two partitions at one side than at the other, the greater distance being shown at the right 110 in Fig. 2. The partition 30 is secured to angle iron supports at the bottom, sides and top, as indicated at 31, 32, 33, and its top is almost level with the lower face of the fan 11. The bottom of the partition 115 26 is spaced from the bottom of the partition 30, a distance equal to about one seventh (1/7) of the distance from the lower face of the fan 11 to the bottom of the partition 30.

As a result of the arrangement just described, it will be seen that an air current generated by the fan 11 will pass downwardly within the partition 26 and then divide and curve outwardly and ascend at 120 each side between the partition 26 and the larger partition 30. These ascending currents, upon reaching the top of the partition 30, will be drawn inwardly by the suction 125 of the fan and pass along the slanting por-

tions 29 of the partition 26 until they enter the top of the fan and are again started on the original downward course. The course of the air currents just described is indicated by arrows in Fig. 2.

Means is provided for heating the air within the enclosure 1, and this means preferably consists of cast iron radiators 34, 35, 36, 37. The radiators 34 and 36 are supported upon angle bars 38 secured to the framing at opposite sides of the enclosure; while the radiator 35 is mounted on angle bars 39, similarly secured, and the radiator 37 on angle bars 40 also secured to the framing at opposite sides. The angle bars 38 are fastened to the exterior of the framing and the angle bars 39 and 40 of the interior thereof. The upper and lower pipes of the radiators may be capped by suitable angle irons 34°, 35°, 36° and 37°. It will be noted that the radiator 37 is of twice the capacity of the other radiators, so as to provide extra heat at this part of the enclosure for a purpose to be hereinafter described. I prefer to equip each radiator with its own controlling means so as to be able to regulate the supply of steam to each independently of the others, for the purpose of varying the temperature in different parts of the enclosure when desired. Such controlling means may be of any well known or approved form, either manual or automatic as desired; one of them being conventionally represented by the valve 33**, Fig. 4. I also prefer to attach steam traps to the discharge end of each radiator so that the water of condensation may pass out of the coil while the trap retains the pressure within the radiator, thereby securing the maximum heat output with a minimum number of radiators, and thus also effecting an economy. This provision of a steam trap for each radiator also eliminates back pressure, which might permit one radiator to work against another.

The apparatus also includes an endless carrier for transporting the articles to be dried through the enclosure in a circuitous path. This endless carrier takes the form of a pair of sprocket chains 41, 42. Each of these chains is endless, and each passes around a set of sprockets located at each side of the housing 1 within the walls thereof. One set of these sprockets is shown in Fig. 2 and is represented by the numbers 43, 44, 45, 46, 47, 48, 49, 50 and 51. It will be understood that the other set of sprockets is exactly like that just described and similarly mounted at the opposite side of the housing. The said sprockets are mounted on shafts 52, 53, 54, 55, 56, 57, 58, 59 and 60, which are journaled in bearings carried at the opposite sides of the housing exterior to the walls thereof. One set of the said bearings is illustrated in Fig. 2 and denoted

by 61, 62, 63, 64, 65, 66, 67, 68 and 69. It will be understood that the other set of bearings is exactly like the set just described and similarly mounted at the opposite side of the housing. As a result of this construction, the shafts 52 to 60 inclusive, transversely disposed in the housing, together with their sprockets, constitute a circuitous course of travel for the said chains, which course is partly without the two partitions 26 and 30, partly between the said two partitions and partly within the partition 26.

In order to provide means for actuating the chains 41, 42, so as to cause them to traverse their endless course, a gear 70 is fixed to the shaft 58 and is driven by a worm 71 which is fast on a vertical shaft 72 that is mounted in bearings 73, 74 exterior to the housing 1. This shaft 72 has a worm wheel 75 fixed to the upper end thereof, which wheel is driven by a worm 76 fast on a shaft 77 that is mounted in brackets 78, 79, formed integral with cross frames 80 that are laid on the top of the housing 1. The shaft 77 carries a stepped pulley 81, which is connected by means of a belt 82 with another stepped pulley 83 fixed on a shaft 84 that is mounted in brackets 85, 86, formed integral with the cross bars 23. This shaft 84 also carries fast and loose pulleys 87, 88, either of which may be connected by means of a belt 89 with fast and loose pulleys 90, 91 on the shaft 20. As the shaft 20 is actuated by the motor 21, as already described, it will be seen that the connections detailed provide means for driving the gear 70 and its transverse shaft 58 from the said motor, which means may be disconnected at will by moving the belt 89 from the fast pulleys 87, 90, to the loose pulleys 88, 91. Suitable belt shifting devices may be provided in the customary manner, and it will be observed that variations in speed of the shaft 58 may be obtained by shifting the belt 82 on the pulleys 81, and 83, in addition to varying the speed of the motor 21, so that the chains 41, 42, may be caused to transverse their sinuous course at the desired rate of speed.

The bearing 64 and its mate which carry the shaft 55 are made slidably adjustable in boxes, one of which is illustrated at 92, and screws, one of which is marked 93, are provided for adjusting the said bearings. By this means, the chains 41, 42 may be kept at the desired degree of tightness. In order to support the lower parts of the chains, which extend along above the bottom of the enclosure, I provide sets of idle sprockets, one set being shown in Fig. 2 and marked 94. These idle sprockets are mounted on stub shafts 95, which project inwardly from the sides of the enclosure, and serve to properly support these long sections of the chains.

without appreciable wear on the parts. I find it advantageous to mount all the sprockets on roller or ball bearings in order to eliminate unnecessary friction and promote the smooth and economical operation of the machine.

I provide suitable trays for carrying the articles to be dried and these trays comprise end members 96 that have apertures 97 fitted to receive pins 98 which are secured to and project inwardly from the chains 41, 42. This provides a pivotal connection between the members 96 and the chains. The members 96 are preferably composed of cast iron and have inwardly projecting flanges 99 to which are secured wooden shelves 100 by means of bolts 101. These wooden shelves are provided with perforations 102 which are arranged in staggered relationship, in order to permit access of the drying air to the articles, as will be hereinafter described.

These shelves 100 constitute means for directly supporting the molds, denoted by 103, upon which the articles to be dried, such as plates 104, are laid after they have been formed from the ceramic material, and it will be seen that the molds with their articles may be placed upon the shelves 100 of the trays as the latter pass the feed opening 105 which is formed in the wall of the housing 1, and be removed from the said trays, after the drying operation, as the trays pass the discharge opening 106.

55 The distance between the sprockets 43, 45, 47 and 49, considered in a direction parallel to the longitudinal axis of the enclosure 1, is less than the diameter of the sprockets and the same is true of the space 40 between the sprockets 44, 46 and 48. This results in the fact that the paths of travel of those parts of the chains 41 and 42 within the partitions 26 and 30, are not exactly vertical, but are slightly angular. This arrangement causes the trays 96-102 to swing out slightly, under the force of gravity, so that successive trays are not exactly in line with each other, in order to provide better contact with the drying air, as will be hereinafter described.

Baffles 107 may, if desired, be located between the partitions 26 and 30 in order to give the ascending currents a zig-zag course and improve the contact of the drying air 55 with the articles. These baffles are preferably composed of some material such as rubber belting and are attached to the partitions by small angle irons. It will be noted that these baffles are arranged at an angle 60 to the partitions so that they slope upwardly and that each baffle is longer than the next one below it. This arrangement tends to promote an even zig-zag flow of the air current.

65 The partition 30 is composed of thermo-

insulating material, and while it is conventionally illustrated it will be understood that I prefer to construct it of plates like the plates 3. This prevents the heat generated by the radiators 34, 35, 36, 37, 70 from being transmitted to the exterior channel, which is bounded by the partition 30 on the one hand and by the walls and bottom of the enclosure 1 on the other hand. This channel is substantially U shaped and its 75 vertical side parts are denoted by 108, 109, and the horizontal bottom part by 110.

Thermo-insulating plates 111 like the plates 3, are also arranged in trough-like form transversely of the enclosure above 20 the fan. The sloping sides of this trough-like arrangement serve to guide the returning air currents to the top of the fan 11, and the fact that it is composed of thermo-insulating material also prevents the bearing 13 and motor 21 from becoming too hot.

In operation, a suitable amount of steam is supplied to the radiators 34, 35, 36 and 37, and the fan 11 and chains 41, 42, are actuated by their driving mechanism. The workman standing by the feed opening 105 places the plate 104 or other articles to be dried on its mold 103 which latter is resting on a shelf 100 of a tray. This operation is repeated until all the shelves are 25 suitably loaded with the articles to be dried resting upon their molds. During this operation, the trays with their shelves 100 are passing slowly upwardly by the feed opening 105 in the part 108 of the channel 100 exterior to the partition 30, and it will be noted that while in this part of the channel, the plates are out of contact with the heated air currents though subjected to a somewhat elevated temperature. This is a 105 feature of importance, since it is desirable that the plates should not be subjected to too great a heat at this initial stage of their drying operation. After the plates have 110 passed the sprocket 43 and are descending between the partitions 26 and 30, they come 115 in contact with an ascending current of heated air, but this current is not as hot as that which is to be encountered at a later stage of travel, owing to the location of the 120 radiators. While in this travel from the sprocket 43 to the sprocket 44, it will be 125 noted that the air current is moving in a direction toward the bottoms of the shelves 100, so that although the plates are subjected to elevated temperature, they are 130 protected to a certain extent by the shelves and molds from direct contact with the air current, thus preventing injury to the plates. The perforations 102 in the shelves 100 permit the access of a certain amount of heated current to the under-side of the molds and thus suitably warm them simultaneously with the heating and drying of 135 the plates. The fact that the trays with 140

their shelves 100 stand slightly out of vertical alignment with each other, owing to the angular path of travel of the chains already described, enables the heated current to have better access to each tray, since it is not so fully protected by the next tray below; and this attitude of the trays also tends to cause the shelves to act as baffle plates in addition to the baffles 107, and impart to the heated current a somewhat irregular or zig-zag course, which promotes its drying effect.

As the plates pass beneath the sprocket 44 and enter upon their first upward course within the partition 26, they come into direct contact with the descending air currents but, by this time, they have been sufficiently heated so that no injury results from this direct contact. At this juncture the plates also begin to be subjected to an increased temperature owing to the presence of the radiators within the partition 26. Furthermore, the plates have, by this time, begun to shrink somewhat and become slightly separated from their molds at the edges, thus permitting the hot air current, which impinges directly against the plates and molds to enter between the same and dry the plates upon the inside. The conditions just described prevail substantially continuously during the passage of the plates throughout their course within the partition 26, and it may be added that the relatively small space which exists between the bottom of the partition 26 and the partition 30 gives rise to a tendency to an increase of air pressure within the partition 26, which pressure forces the heated air into intimate drying contact with all accessible portions of the plates. As the plates pass around the sprocket 48 and start their upward course between the partitions 26 and 30, they come under the influence of the large radiator 37 and are thus subjected to the highest heat at any time during their course of travel. This brings about the final drying of the plates and, after they round the sprocket 48 and pass downwardly in the part 109 of the channel exterior to the partition 30, they may be moved by an attendant, from the shelves of the trays at the discharge opening 103.

Following the removal of the plates, the trays, with the molds therein, pass on through the remainder of the part 109 of the exterior channel, through the part 110 of the said channel and enter the part 103 thereof, in order to pass the feed opening 105 for a second loading. As already mentioned, the walls of the partition 30, within which all the radiators are situated, are insulated so as to prevent the radiation of heat into the said channel and, therefore, during the passage of the trays through the

channel back to the feed opening 105, the molds therein are cooled. This is an important consideration, since the plates might be injured if they were placed, at the outset, upon molds of too high temperature.

It will be understood that the operation just described may be a continuous one, the loading and unloading taking place at opposite ends of the enclosure simultaneously. I would call attention to the fact that the general scheme of arrangement is such that the plates or other articles to be dried are at first subjected to a fairly low temperature, and that, as they continue on their course, the temperature encountered is higher and higher until the stage is reached at which the articles are passing the large radiator 37. Furthermore, the arrangement is such that the articles are not subjected to the full force of the air current until they have become heated and dried to a considerable extent.

I have specifically mentioned the beneficial effect of the somewhat slanting course of travel during the passage of plates from sprocket 48 to sprocket 44, but it will be clear that the advantage thus mentioned is also maintained throughout the remainder of the travel from sprocket to sprocket, since this arrangement increases the efficiency of the drying air current.

As already mentioned, the drive for the fan is separable from the drive for the chains 41, 42 by shifting the belt 89 from the fast pulleys 87, 90 to the loose pulleys 88, 91, so that the travel of the trays with the articles thereon, may be stopped and yet the fan continue in operation. This is of extreme importance, since if the travel of the trays were stopped and the fan also stopped, those articles which were near any one of the radiators would be apt to be warped or otherwise injured by the excessive heat. The continuous operation of the fan prevents this, since it insures the continued movement of the air current and thereby distributes the heat from the radiators.

Thus I have provided an apparatus which is comparatively small in size when its capacity and output are considered, which is continuous in operation, in which a progressive drying operation is effected so as to produce uniform and uninjured products, and which is insulated so as not to noticeably increase the temperature of the room in which it is located.

Referring to the modified form shown in Figs. 10 to 14, inclusive;—The general structure and arrangement is the same as that already set forth in describing the preferred form, but it will be noted that additional sprockets, two of which are illustrated at 112, 113, are mounted immediately above and below the feed opening, which is

denoted in this case by 114, and extends entirely across the end machine. Angle bars, one of which is denoted by 115, project at each side of the enclosure 1, at the height of 8 the feed opening 114 and carry at their ends bearings, one of which is marked 116, in which is mounted a shaft 117, upon which is fixed a pair of sprockets, one of which is shown in Fig. 10 and marked 118. 10 The chains, one of which is shown and marked 119, pass around the sprockets 112, 113, 118, and their mates, with the result that the course of the trays carrying the articles to be dried includes a section which 15 is exterior to the enclosure.

This arrangement is particularly desirable in case the apparatus is used as a mangle, that is, for drying the articles after they have been dipped in the glaze. The 20 glaze tub is conventionally represented at 120, and it will be seen that the operator can dip the articles in the glaze and then place them upon the trays as the latter pass around the sprocket 118 without having to 25 reach into the machine. This is a great advantage when two tubs of glaze are being used. Furthermore, this permits the glaze to drip from the articles immediately after they have been placed on the trays, back into 30 the tub 120, instead of down onto the articles on the succeeding tray, because at the time each tray is loaded, it stands out beyond the succeeding tray and over the tub 120, as indicated at the extreme left in Fig. 10.

35 In this form, I also prefer to use a modified tray which consists of a pair of similar brackets 121 that are hung on the pins 97 which project from the chains as described in connection with the preferred form. 40 Each of these trays has one shelf 122 which is composed of a series of slats. The central slats have sets of pins 123 upstanding from one side thereof so that shallow dishes, such as plates, may be stood on edge, as indicated in dotted lines, Fig. 13. This attitude 45 of the plates, in connection with the slotted or perforated structure of the shelf 122, permits the drying air current to have free access to all surfaces of the plates, and only 50 requires the plates to have small surface contact with the shelf. This is particularly 55 advantageous in connection with a flat article, since if it were set flat on the shelf 122, the latter would cover a considerable portion of its surface. The shelf 122 engages the brackets 121 by means of trunnions 124 which are fitted to travel in slots formed in the brackets 121; and the said brackets are bifurcated and bent at right 60 angles at their lower parts so as to provide a resting place for the ends of the shelf 122. This construction enables the shelves 122 to be reversed, which is accomplished by lifting the shelf upwardly with respect to the 65 brackets 121 until it is at a sufficient height

above the lower part of the said brackets so that it may be rotated on its trunnions 124 without engaging the lower part of the bracket. When at this height the shelf may be turned over and permitted to slide down 70 again onto the lower part of the brackets. The two positions of the shelf are clearly shown in Figs. 13 and 14, and the half-way position is represented in dotted lines, Fig. 12. When the shelf has been reversed to 75 the position shown in Fig. 14, it presents a smooth or ribbed surface upon which relatively high articles such as cups (shown in dotted lines, Fig. 14) may be placed, after 80 they have been dipped in the glaze, and satisfactorily dried; the apertures between the slats which compose the shelf permitting ready access of the drying air to articles of this character.

85 Referring to the modified form shown in Fig. 15, it may be said that this is in principle substantially like the preferred form shown in Figs. 1 to 9 inclusive. There are, however, some points to which attention may be directed.

90 The enclosure, which is denoted by 125 is intended to be of the same construction as the preferred form. The inner partition, which corresponds to and is of the same construction as the partition 26, is marked 126 and consists of a pair of members which project downwardly from the top of the enclosure for a relatively short distance. The outer partition 127, which corresponds to 95 and is of the same construction as the partition 30, has square corners and is hung from the supports for the shafts that carry the four end sprockets in the upper rows. An additional single partition 126* is placed 100 in the centre of the enclosure and spaced 105 from the bottom of the partition 127 and the top of the enclosure.

110 The sprockets are denoted by 128, 129, 130, 131, 132, 133, 134, 135, 136, 137 and 138, and it will be noted that there are five sprockets 115 in the upper row and four sprockets in the lower row within the partition 127. The general arrangement of the sprockets is clearly shown in Fig. 15. Lower supporting sprockets 139 are also provided. There 120 are two chains as in the preferred form, one of which is shown in Fig. 15 and marked 140. The trays 141 are pivoted to the chains and are conventionally represented.

125 Six radiators 142, 143, 144, 145, 146, 147 are placed within the partition 127 and located between various sections of the course of travel of the chains. These radiators are somewhat conventionally represented, but it will be understood that they may be constructed and mounted as shown and described in connection with the preferred form. It will also be observed that the radiators 142 and 143 are smaller than the remaining radiators, thus providing for an 130

increase of temperature as the articles progress through the enclosure.

The fan is represented by 148 and is mounted in a vertical plane on a shaft 149 that is supported by brackets 150 on the top of the enclosure 125. The enclosure is provided with a gabled portion 151, which houses the fan and through which the shaft 149 extends with a comparatively close fit. The shaft 149 is driven through a pulley 152 fast thereon, a belt 153, and pulley 154 fixed on a power shaft 155 that is mounted in suitable supports 156. Guide pulleys 157, 158 mounted in a support 159 are provided for the belt 153.

The chains are driven by means of a gear 160 that is fast on the shaft carrying the sprocket 136, which gear is actuated by a worm 161 on a shaft 162. This shaft has a worm wheel 163 fixed thereon, which meshes with a worm 164 that is fixed on a shaft 165 mounted on top of the enclosure 125. A stepped pulley 166 is fast on the shaft 165 and connected by means of a belt 167 with another stepped pulley 168 that is fixed on a shaft 169 mounted in brackets 170 secured to a suitable support. Another pulley 171 is also fixed on the shaft 169 and connected by means of a belt 172 with a pulley 173 that is fast on the power shaft 155. A loose pulley (not shown) is also mounted on the shaft 155 beside the pulley 173, so that the drive for the chains may be separated from the drive for the fan, when it is desired to stop the movement of the chains and yet keep the fan in operation. The feed opening is denoted by 174 and the discharge opening by 175.

The course of the air currents is indicated by arrows and it will be noted that the gabled portion 151 of the enclosure cooperates with the partition 126 to direct the air current downwardly away from the fan at the start and upwardly toward the fan at the end of the cycle of flow, while the single partition 120* serves to cause the current to take one open circular course instead of two open circular courses, as is the case in the preferred form. In spite of the differences mentioned, the operation of this modified form is substantially the same as the preferred form, and the manner of loading and unloading the machine is the same.

Referring to the modified form of shelf shown in Fig. 16, it will be seen that it consists of a solid piece denoted by 176, which is provided with a series of transverse grooves 177, which grooves are V shape in cross section at their upper parts and rectangular in cross section at their lower parts. This form of shelf is particularly advantageous in connection with the drying of cylindrical articles, such as the insulating blocks of spark plugs, since the form of grooves

permits circulation of air beneath the said blocks so as to uniformly condition the same. Articles of this character are represented in dotted lines in Fig. 16.

With reference to all the forms, it may be mentioned that the entire structure is preferably composed of metal with the exception of the shelves of the trays which are preferably composed of wood and the thermo-insulation which is preferably composed of asbestos. The inner faces of the walls of the enclosure and all the partitions are, as already indicated, preferably composed of galvanized steel and the radiators of cast iron, for the purpose of preventing rusting of the parts. The pins 123 in the form of tray shown in Figs. 11 to 14 should be composed of copper.

As already indicated, in Figs. 2, 10 and 15 of the drawings, only one set of chain and sprocket construction with the attendant parts is illustrated, but it will be understood that the corresponding set located at the opposite side of the enclosure is identical in all respects.

Again referring to all the forms, I desire it to be understood that various changes may be resorted to in the form, construction and arrangement of the several parts, without departing from the spirit and scope of my invention and hence I do not intend to be limited to the details herein shown and described, except as they may be included in the claims.

What I claim is:

1. Apparatus of the character described comprising, an enclosure and a plurality of substantially U shaped partitions therein, one of said partitions being within another, said partitions being devoid of right angles in cross sectional shape. 100 120

2. Apparatus of the character described comprising, an enclosure and a plurality of substantially U shaped partitions therein, one of said partitions being oppositely disposed with respect to the other, said partitions being devoid of right angles in cross sectional shape. 110

3. Apparatus of the character described comprising, an enclosure and a plurality of substantially U shaped partitions therein, one of said partitions being within another and oppositely disposed with respect to the other, the said inner partition being inverted, said partitions being devoid of right angles in cross sectional shape. 115 120

4. Apparatus of the character described comprising, an enclosure and a plurality of substantially U shaped partitions therein, one of said partitions being within another, a fan located within the inner partition for generating an air current, radiators located within the partitions, part of said radiators being located within the inner partition 125

and part being located between the inner and outer partitions.

5. Apparatus of the character described comprising, an enclosure and a plurality of substantially U shaped partitions therein, one of said partitions being within another and oppositely disposed with respect to the other, the said inner partition being inverted, a fan located within the inner partition 10 for generating an air current, and radiators located within the partitions, part of said radiators being located within the inner partition and part being located between the inner and outer partitions.

15 6. Apparatus of the character described comprising, an enclosure and a plurality of substantially U shaped partitions therein, one of said partitions being within another, a fan located within the inner partition 20 for generating an air current, radiators located within the partitions, part of said radiators being located within the inner partition and part being located between the inner and outer partitions, a radiator located between the inner and outer partitions being of greater capacity 25 than any single radiator located within the inner partition.

7. Apparatus of the character described comprising, an enclosure and a plurality of substantially U shaped partitions therein, one of said partitions being oppositely disposed with respect to another, a fan located 30 within the partitions for generating an air current, and radiators located within and between the partitions, a radiator located between the partitions being of greater capacity 35 than any single radiator located within the inner partition.

ity than any single radiator located within the partitions.

8. Apparatus of the character described comprising, an enclosure and a plurality of substantially U shaped partitions therein, one of said partitions being within another and oppositely disposed with respect to the other, a fan located within the inner partition 40 for generating an air current, and radiators located within the partitions, part of said radiators being located within the inner partition and part being located between the inner and outer partitions, a radiator located between the inner and outer partitions being of greater capacity 45 than any single radiator located within the inner partition.

9. Apparatus of the character described comprising, an enclosure and a plurality of substantially U shaped partitions therein, one of said partitions being within another and oppositely disposed with respect to the other, the said inner partition being inverted, a fan located within the inner partition 50 for generating an air current, and radiators located within the partitions, part of said radiators being located within the inner partition and part being located between the inner and outer partitions, a radiator located between the inner and outer partitions being of greater capacity 55 than any single radiator located within the inner partition.

In testimony that I claim the foregoing as my invention, I have signed my name this 19th day of January, 1920.

JOSEPH L. BUCKLEY.
